APPARATUS FOR BURNING FUELS

Albert L. Baker, Summit, N. J., assignor to Gasoline Products Company, Inc., Jersey City, N. J., a corporation of Delaware

Application December 17, 1937, Serial No. 180,277

4 Claims. (Cl. 158—1)

This invention relates to improvements in apparatus for heating fluids and particularly for converting higher boiling hydrocarbons into lower boiling hydrocarbons.

In the treatment of hydrocarbons it is customary to locate tubes on the walls of a furnace so that the tubes will be exposed to radiant heat or hot combustion gases or both. Burners are provided for burning fuel in a combustion chamber or zone to provide the heat necessary to raise the temperature of the hydrocarbon fluids in the tubes.

According to my invention a plurality of burners comprising sets of opposed fuel nozzles is provided, each nozzle preferably having a series of openings which are set at an angle to the horizontal so that the fuel streams are projected downwardly into the combustion chamber of a furnace and mixed with air to produce flames having the desired characteristics.

In the preferred form of my invention there is a plurality of burners each having a pair of parallel fuel nozzles, each nozzle preferably being elongated and provided with a plurality of orifices which are adapted to direct thin, wide streams of fuel into the combustion zone in a furnace. The streams of fuel may intersect within the combustion zone to form one type of flame or the nozzles and orifices may be arranged to have the streams pass by each other in opposite directions to form a different type of flame.

The fuel nozzles are preferably placed at the top of the furnace to provide down firing whereby additional space is provided on the floor of the furnace for heating tubes, but the fuel nozzles may be positioned at other places in the furnace.

By having opposed fuel nozzles each having its own fuel supply, the pressure on the fuel and the amount of fuel delivered to any nozzle may be varied and in this way the flame and flame pattern may be changed; and by maintaining the pressures on the fuel delivered to each nozzle I can maintain the flame which is desired or which will give the best results. With sets of opposed fuel nozzles, greater flexibility in the control of the flame length, flame direction and flame pattern for varying furnace capacities is provided.

In addition I have provided means whereby one nozzle in each set may be moved longitudinally of the other nozzle in the set so that the fuel streams from the orifices are offset and not directly opposed and in this way a short, wide and thick flame may be obtained.

The tubes located in the combustion zone or

radiant section of the furnace are located substantially out of the path of the hot gases and are heated predominantly by radiant heat, while those in convection section are swept by hot products of combustion and the tubes are heated by absorbing heat from such gases. It is desirable to have a hot flame in the combustion zone which may be varied as desired to provide radiant heat for selected sections of the tubes which, for example, may be ordinarily hard to heat. But it is important not to have the flame impinge on the tubes as this causes overheating of, and damage to, the tubes.

A method of burning fuel in a furnace having tubes for heating hydrocarbon fluids contemplated by my invention includes selecting a pressure on the fuel fed to one of the nozzles in a burner to obtain a desired flame which may be directed to a selected set of tubes to produce the desired heating of the hydrocarbon fluids. In operating a furnace according to my invention the flame size, flame length and flame pattern can be varied to produce the best heating conditions for the tubes.

Other features and advantages of my invention will be pointed out hereinafter in the detailed description.

In the drawings:

Figure 1 represents a vertical cross-section taken through a furnace embodying my invention;

Figure 2 represents a vertical cross-section taken substantially on line 2—2 of Figure 1 with the wall tubes omitted to facilitate the disclosure;

Figure 3 represents a vertical transverse cross-section taken through a burner of another form adapted to be mounted on the roof tubes on a furnace; and

Figure 4 represents a longitudinal vertical cross-section taken substantially on line 4—4 of Figure 3.

Referring now to the drawings, the reference character 10 designates a furnace having a main heating chamber or radiant section 12 and a convection section 14 separated by a bridge wall 16. Banks of roof tubes 18, wall tubes 20, 22 and floor tubes 24 are provided in the radiant section 12 of the furnace. The cross-over connections 25 for the ends of the tubes are preferably enclosed in insulated housings 26. Banks of tubes 28 are located in the convection section 14 of the furnace. An outlet 29 is provided for conducting the products of combustion from the furnace.

Sets of opposed nozzles 30 and 31 forming burners 32 are provided at the top of the furnace 10

for burning fuel such as gas, oil or the like to supply heat to the furnace, the burners being spaced longitudinally of roof tubes 18 and preferably positioned at one end of the radiant section 12 of the furnace 10. The burners shown in Figures 1 and 2 will be first described. The burners are mounted in an air duct generally indicated by 34 which will be later described in more detail. Each nozzle has flared sides 35 which terminate in an elongated member 36 having a straight line of orifices or openings 38 which are directed downwardly at an angle of about 30 to 35° to the horizontal. The elongated members 36 of each burner are arranged in parallel relation. The orifices 38 are adapted to direct fuel streams toward each other so that the fuel streams intersect within the combustion chamber 12 of the furnace 10 when the orifices of the opposed nozzles are in alignment.

The nozzles of each burner are preferably mounted on two adjacent roof tubes, each nozzle having a leg 40 engaging the top of one of the roof tubes. The legs 40 extend through slots 41 in the air duct casing 34. Each nozzle may have its own source of fuel feed. For instance, in the burner shown in Figure 1, nozzle 30 is connected to and communicates with a pipe 42 having a valve 44, and nozzle 31 is connected to and communicates with a pipe 46 having a valve 48. The pipes 42 and 46 may be supported by the air duct 30 casing 34. By having individual feed pipes 42 and 46, the pressure on the feed and the quantity of fuel fed to one nozzle of a set may be varied to change the flame pattern, flame length, flame direction, etc., to produce the desired heating. A plurality of burners is mounted on roof tubes as shown in Figure 2 preferably in alignment. If desired, instead of having individual valves for the individual burners, a master valve control may be provided for sets of burners.

The air duct casing 34 has a main feed conduit 52 which feeds into spaced air ducts 54 to the individual burners. The casing 34 has inwardly directed bottom portions 56 for directing the air toward the fuel streams issuing from the nozzles 30, 31 of the burners 32. The casing 34 may be supported in any suitable manner.

Air under any suitable pressure is forced into the main feed conduit 52 and then is conducted to the individual air ducts 54 in which the burners 32 are mounted. If desired, a main damper 58 may be provided for the main feed conduit 52 and auxiliary dampers 60 having actuating arms 62 may be provided for the individual air ducts for controlling the amount of air delivered to the individual air ducts and burners.

When the orifices in opposed nozzles of each set are directly opposite, a relatively long flame will be obtained, the direction of which can be changed by varying the pressure on the fuel fed to the nozzles. By offsetting the orifices so that they are not directly opposite, the flame pattern can be changed. This effect is obtained by moving one nozzle with respect to the other so that the fuel streams from the orifices in one nozzle will be offset with respect to the fuel streams from the other nozzle of the burner and the fuel streams will pass by one another in opposite directions and a wide, thick and relatively short flame will be obtained.

In the form of burner shown in Figures 1 and 2 I have shown means for moving one of the nozzles with respect to the other nozzle of a burner which will now be described generally in connection with Figures 1 and 2 and later more particularly in

connection with Figures 3 and 4 where the means is illustrated in more detail on a different form of burner. For purpose of illustration I have shown one form of means for moving one of the nozzles but it is to be expressly understood that I am not restricted thereto as many other constructions may be used to obtain this result. With this means one nozzle may be moved so that the orifices of the nozzles are either directly opposed or offset.

An operating member 66 is provided for each burner and is pivotally mounted at 68 on projection 70 which extends from the wall of the air duct 54. The lower end of the operating member 66 is pivotally connected to a horizontally extending arm 72 which extends through the wall of the air duct 54. The inner end of the arm 72 is pivotally connected to the top of a vertically arranged arm 74 pivotally mounted intermediate its ends at 76. The lower end of the arm 74 is pivotally connected at 78 to nozzle member 30. The operating member 66 has a securing means at 80 for holding the operating member in adjusted position. By moving the operating member 66 to the left or right in Figure 2, it will be seen that the nozzle member 30 may be moved longitudinally of the roof tube 81 of the furnace. Nozzle member 31 is fixed in its position and with operating member 66, nozzle 30 can be moved relatively to nozzle member 31.

In Figures 3 and 4 I have shown a modified form of burner for the furnace. This burner comprises an enclosed box-like chamber 82 open at its bottom portion and having a top wall 84, side walls 86 and end walls 88. The box-like member 82 is provided with curved arms 90 which straddle the roof tubes 81 and which hold the burner in position on the roof tubes.

A pair of nozzles 92 and 94 is provided. Each nozzle comprises an elongated tubular member 96 provided with a series of orifices 98 which are directed at an angle of about 30° or 35° to the horizontal so that streams of fuel are directed downwardly and in a general direction toward each other as shown by arrows in Figure 3. Bracket members 100 and 102 are provided for mounting the tubular members 96 on the side walls 86 of the box-like enclosing means 82. These brackets include curved arms 103 which embrace the nozzle members. The outer ends of the bracket members are threaded as at 104 to receive nuts 105. The brackets 100 hold the nozzle member 92 somewhat loosely in position in order to permit longitudinal movement of the nozzle member 92 relatively to nozzle member 94 for adjustment purposes as will be presently described. The brackets 102 for the opposed nozzle 94 rigidly hold nozzle 94 in position.

Pipe members 110 and 111 connected to the respective nozzle members 92 and 94 are provided for supplying fuel to the respective nozzle members. Valves 112 and 113 are provided in the pipes 110 and 111 whereby the pressure on the fuel and the amount of fuel admitted to the nozzle members may be varied. An air duct 114 extends through the end wall members 88 of the enclosing means 82 and is provided with an opening 116 for introducing air to the burner. The burner shown in Figures 3 and 4 operates in substantially the same way as the burner shown in Figures 1 and 2 and means are included for moving one nozzle member relatively to the other nozzle member of the burner.

The means for adjusting the nozzle member 92 with respect to nozzle member 94 will now be

described. A base member 120 secured to the outer face of one of the end walls 88 serves as the mounting for an operating member 122 pivotally mounted at 124. The base member 120 is provided with a slot 126 through which extends a wing nut member 128 for holding the operating member in adjusted position. The lower end of the operating member 122 is pivotally connected at 130 to a horizontally arranged arm 132 which extends through the end wall 88 into the interior of the enclosing means 82. The inner end of the arm 132 is pivotally secured to a vertically arranged member 136. The vertically arranged member 136 is pivotally mounted intermediate its ends at 138 on a member 139 secured to the inner surface of the end wall 88. The lower end of the vertically arranged member 136 is provided with a vertical slot 142 for receiving a pin 144 secured to spaced members 146 which are rigidly secured as by welding to one end of the nozzle member 92. From the foregoing description it will be seen that when it is desired to move the nozzle member 92 longitudinally of the roof tube 91, the wing nut 128 is loosened and operating member 122 moved either to the left or to the right in Figure 4 and this will cause corresponding movement of the nozzle member 92. For example, moving the operating member 122 to the left in Figure 4 moves the lower end thereof and arm 132 to the right and this in turn moves the top of vertical arm 136 to the right and the lower end thereof to the left. As the lower end of arm 136 is connected to the nozzle member 92, the nozzle member 92 will be moved to the left longitudinally of the roof tube 91 and relatively to the other nozzle member 94.

An opening 149 having a cap 150 is provided adjacent the burners 32 for introducing a torch or the like for lighting the fuel introduced into the furnace.

While I have shown only one burner in Figures 3 and 4, it is to be understood that in firing a furnace a plurality of such burners will be used and they may be positioned along the roof tubes of a furnace as shown in Figures 1 and 2.

While I have shown burners for firing a furnace, it is within the contemplation of my invention to use a single burner having the control features above described in an apparatus where one burner would be sufficient.

The method of operating the burners of my invention including a method of firing a furnace will now be given. With hydrocarbon fluid passing through tubes 18, 20, 22 and 28, fuel is introduced into the nozzle members 30 and 31 in Figure 1 and air is introduced into the main air duct 34. A lighted torch or the like is introduced through the opening 149 to ignite the fuel and the torch is then removed. After the fuel stream is ignited, a flame is produced by each burner 32 which can be varied by changing the pressure on the fuel streams introduced through lines 42 and 46 or by changing the relative positions of the nozzle members of each burner. With the apertures or orifices 38 of the nozzle members 30 and 31 directly opposite and with the pressure on the fuel passing through lines 42 and 46 to nozzles 30 and 31 of each burner 32 substantially equal, a flame will be obtained which extends substantially along the axis 151 shown diagrammatically in Figure 1. With the nozzle members 30 and 31 in the same position and by increasing the pressure on the fuel introduced to nozzle member 30 through line 42, the resulting flame will be moved to the right in Fig-

ure 1 so that the axis of the flame is generally along line 152 shown diagrammatically in Figure 1. If it is desired to direct the flame toward the wall tubes 20, the pressure on the fuel introduced to nozzle member 30 may be somewhat reduced and the pressure on the fuel introduced to nozzle member 31 through line 46 is increased so that the flame will be moved toward the left in Figure 1 and the flame will extend substantially along the line 154 as an axis shown diagrammatically in Figure 1. The products of combustion from the flames will follow the general path indicated by arrows 156 to the convection section 14 of the furnace where heat will be absorbed by tubes 28 and then out through the outlet 29 of the furnace.

If it is desired to vary the flame pattern and obtain a short, thick and wide flame, nozzle member 30 is moved with respect to the nozzle member 31 by actuating operating member 66 so that the orifices 38 in the nozzle member 30 are offset with respect to the orifices in the opposed nozzle member 31 and not directly opposite thereto. It is only necessary to move nozzle member 30 a short distance. The fuel streams from the apertures or orifices 38 of the nozzle members will then pass one another and a shorter flame will be obtained along the axis 151 when the pressures on the fuel streams introduced to the nozzle members 30 and 31 are substantially the same. By varying the fuel pressures and with the nozzle members in the offset position just described, the axis of the short, thick and wide flame will be moved to the right or to the left in Figure 1 as described in connection with the previous operation where the orifices 38 of the nozzle members 30 and 31 were directly opposite, and in this way the type of flame for best heating the tubes or any selected tubes may be obtained.

The burner shown in Figures 3 and 4 operates in substantially the same way as the burner 32 above described and it is not necessary to repeat the operation with respect thereto.

From the above description it will be seen that I have disclosed a method of firing a furnace and a controllable burner which can be used for firing furnaces adapted for heating hydrocarbon fluids but which can be used for other furnaces. The flame produced by the burner can be changed from a relatively long flame to a relatively short flame and the flame direction and flame pattern can be changed so that the heat produced by the flame can be utilized to its best advantage in raising the temperature of the hydrocarbon fluid in the tubes. By changing the flame length, flame direction and flame pattern, I am enabled to provide most heat where desired and to provide radiant heat for selected sections of the tubes, which, for example, may be hard to heat.

While I have shown particular forms of burners it is to be understood that they have been shown for purposes of example only and may be changed and modified without departing from the spirit and scope of my invention.

I claim:

1. A heating apparatus of the character described including a combustion chamber, a burner for said combustion chamber and comprising spaced substantially parallel nozzle members, each of said nozzle members being provided with a series of orifices through which fuel streams pass into said combustion chamber where they intersect when said orifices are di-

rectly opposite each other, means for supplying air for burning the fuel, and means for moving one of said nozzle members longitudinally of the other to offset one series of orifices with respect to the other whereby the fuel streams from said orifices will be offset and will pass each other in opposite directions in said combustion chamber to produce a shorter flame than a flame produced by having the orifices of said nozzle members directly opposite each other.

2. A heating apparatus of the character described including a combustion chamber, a burner for said combustion chamber and comprising spaced cooperating nozzle members adapted to direct streams of fuel toward each other and into said combustion chamber, means for supplying air for burning the fuel, means for supplying fuel to each of said nozzle members under pressure to produce a flame extending along a line forming an extension of the axis of said burner and means whereby the pressure on the fuel supplied to said nozzle members may be varied to change the flame direction, said nozzle members being provided with a series of orifices through which the fuel streams pass, the orifices of the nozzle members in one position being directly opposite each other so that the fuel streams intersect within said combustion chamber, means for moving one nozzle member longitudinally of said other nozzle member so that the fuel streams will not intersect and will be in offset relation to vary the flame pattern.

3. A heating apparatus of the character de-

scribed including a combustion chamber, a burner extending into said combustion chamber and comprising spaced nozzle members adapted to direct streams of fuel toward each other and into said combustion chamber, means for supplying fuel to each of said nozzle members, means for supplying air for burning the fuel and means whereby the pressure on the fuel fed to one of said nozzle members may be increased to control the intensity and pattern of the flame resulting from the burning of the fuel streams, said nozzle members being provided with a series of orifices through which the fuel streams pass, and means for moving one of said nozzle members longitudinally of said other nozzle member whereby the fuel streams from said orifices will be offset with respect to each other and will pass each other in opposite directions in the combustion chamber.

4. A device of the character described including a casing having an outlet, spaced parallel elongated nozzle members adjacent said outlet, means for supplying fuel to said nozzle members, said nozzle members being provided with series of orifices adapted to direct streams of fuel toward each other and through said outlet and means for moving one of said nozzle members longitudinally of the other so that the fuel streams from said orifices may intersect or not whereby the length and pattern of the flame produced by burning the fuel streams may be changed.

ALBERT L. BAKER.
